DESIGN FOR A CARPET.

SPECIFICATION forming part of Design No. 12,489, dated September 20, 1881.

Application filed August 17, 1881. Term of patent 3½ years.

UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,489, dated September 20, 1881.

Application filed August 17, 1881. Term of patent 3½ years.

To all whom it may concern:

Be it known that I, JULIUS PEGEL, of New York, in the county and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a floral group, composed of a rose and other flowers and of many leaves. B is a smaller 15 floral group, placed below the group A. From the upper part of group A extends an L shaped bar, a. Another bar, b, connects groups A and B. To the right of group B is a bar, d, which joins it to a third floral group, C. D is an 20 other floral group, which connects with the bar a and with another L-shaped bar, e, that extends to the group C. The bars a, b, d, and e are each subdivided into small rectangles, as shown. This renders them prominent and 25 makes the effect of dividing the groundwork of the carpet into geometrical fields.

E is a large floral group, located below the group D, and connected with the same by two parallel bars, f. At the left of group E is an 30 angular bar, j, and rectangular ornament l. Below the group E is an angular bar, g, joining it to group C below. Two bent bars, h and i, extend from the group E to a floral group, F. The upper bar, h, also serves to connect 35 groups B and E.

I claim—

1. The design for carpets, consisting of the figure A, substantially as shown.

2. The design for carpets, consisting of the figure B, substantially as shown. 40
3. The design for carpets, consisting of the figures A b B, substantially as shown.
4. The design for carpets, consisting of the figure C, substantially as shown.
5. The design for carpets, consisting of the figures B d C, substantially as shown. 45
6. The design for carpets, consisting of the figures A b B d C, substantially as shown.
7. The design for carpets, consisting of the figure D, substantially as shown. 50
8. The design for carpets, consisting of the figures C e d, substantially as shown.
9. The design for carpets, consisting of the figures D a A, substantially as shown.
10. The design for carpets, consisting of the figure E, substantially as shown. 55
11. The design for carpets, consisting of the figures D f E, substantially as shown.
12. The design for carpets, consisting of the figures C g E, substantially as shown. 60
13. The design for carpets, consisting of the figure F, substantially as shown.
14. The design for carpets, consisting of the figures E h i F, substantially as shown.
15. The design for carpets, consisting of the figures E B h i F, substantially as shown. 65
16. The design for carpets, consisting of the figures A, B, C, D, E, F, a, b, d, e, f, g, h, i, j, and l, substantially as shown.

JULIUS PEGEL.
